INCINERATOR

Joseph K. Blum, Scarsdale, Roger G. Blum, New York, and Donald J. Blum, Scarsdale, N. Y., assignors to Burnwell Incinerator Corporation, New York, N. Y., a corporation of New York

Application April 28, 1950, Serial No. 158,648

5 Claims. (Cl. 110—18)

1

This invention relates to improvements in incinerator installations for buildings and in particular to a novel type of furnace structure for an incinerator having a separate feeding chute and gas discharge flue. This application is a continuation-in-part of our co-pending U. S. Patent application, Serial No. 137,352, filed January 7, 1950.

Our aforementioned patent application disclosed a furnace having artificial means for creating a diverting draft or air current in an incinerator of the "chute" type in which a single chute serves as the feeding chute as well as the gas discharge flue. Our present invention is concerned with similar means as applied to an incinerator in which the feeding chute and flue are separated. In incinerators of the latter type, it is a frequent occurrence that combustion gases and even flames are discharged upwardly through the feeding chute, and consequently cause annoyance to the user, or may even be dangerous.

It is an object of the present invention to provide means for directing a stream of cold air across the bottom of the feeding chute and into the incinerator furnace, said air stream forming an air shield or screen which prevents the hot gases and flames from the incinerator from rising up said feeding chute. The cold air also cools the bottom of said chute so as to reduce the chimney action of the feeding chute and the tendency of said chute to draw gases therethrough. The draft from the discharge flue is, however, left unaffected so that it may draw off all of the combustion gases from the furnace.

Another object of the invention is to provide an incinerator furnace in which the refuse and combustion gases are subjected to an auxiliary flame regulated to maintain a desired furnace temperature which is sufficient to cause the refuse to burn thoroughly and is also sufficient to cause the gases given off in the process of combustion to be completely oxidized.

Still another object of the invention is the provision of an incinerator furnace in which the combustion gases are caused to take a devious course through the furnace to the flue or chute, past baffles and around corners, in order to insure complete combustion of the gases, as well as to cause the major amount of ash to be deposited before it can be carried up the flue or chute.

Other objects and advantages of the invention will be readily apparent in the course of the following specification when taken in connection with the accompanying drawings which illustrate several modifications of the invention which

2

are presented by way of illustration and not in a limiting sense.

Fig. 1 is a vertical section showing an incinerator furnace constructed according to the invention and communicating with feeding and discharge chute which are broken away for convenience of illustration.

Fig. 2 is a partial vertical section of another type of chute arrangement in which the invention may be incorporated.

Fig. 3 is a vertical section showing the invention applied to another type of incinerator.

Fig. 4 is a vertical section showing a simplified type of incinerator furnace in which the invention has been applied.

Fig. 5 is a vertical section showing an incinerator of the type shown in Fig. 1, but including additional features and a modified arrangement.

Fig. 6 is a fragmentary cross sectional vertical sectional view, taken at right angles to Fig. 1 and showing the nozzle in elevation.

Referring in detail to the drawings, and in particular to Fig. 1, the incinerator shown therein has a furnace 10 which communicates at one end with a gas discharge flue 11, and at the other end with a feeding chute 12.

The furnace 10 is generally of the type shown and described in our aforementioned patent application, Serial No. 137,352. The furnace 10, flue 11, and chute 12 may have inner walls 13 made of fire brick, and outer walls 14 made of ordinary brick or other suitable material. The flue 11 and chute 10 need not be lined along the entire vertical surface.

The furnace 10 has an upstanding partition wall 15 which divides the lower interior portion of said furnace into a refuse collection chamber 16, and a gas mixing and combustion chamber 17. A grate 18 extends horizontally across the refuse collection chamber 16 in parallel spaced relationship with the floor of said chamber 16. This grate 18 normally holds a supply of refuse R which is dropped down the feeding chute 12.

A baffle wall 19 serves as the outer wall of furnace 10 and also as a wall of an uptake or connecting flue 20 which is located adjacent the chamber 17. The lower end of said baffle wall 19 contains a gas passage or opening 21 which connects said chamber 17 and flue 20. The uptake flue 20 extends vertically above the top of the furnace 10, and communicates with a transverse extension or conduit 22, which in turn communicates with the bottom of the gas discharge flue 11. The wall of transverse conduit 22 may be en-

cased in a metal pipe or sleeve 23 for increased stability and strength.

The furnace 10 is also provided with an externally-located fuel burner (not shown) whose nozzle 24 extends through the wall of furnace 10 into the interior thereof. The nozzle 24 is positioned to throw a flame over substantially the entire inner area of the furnace, particularly into the refuse collection chamber 16 and the gas mixing and combustion chamber 17.

An air blower 25 is located exteriorly of the incinerator. The blower 25 feeds through a pipe 26 to a plenum chamber 27 located adjacent the lower end of the feeding chute 12. The plenum chamber 27 has a nozzle 28 which extends through an opening 29 in the wall of the chute 12 and is directed into the interior of the bottom of chute 12. The nozzle 28 is preferably as wide as the chute 12 so that it extends the full width of chute 12. The nozzle 28 is pivotable in a vertical plane so that the angle of the stream of air across the chute 12 may be varied. For this purpose also, the opening 29 in the wall of chute 12 is enlarged.

The uptake flue 20 is optionally provided with a damper 30 for controlling the draft within the incinerator, if necessary. The provision of such a damper will depend upon the requirements of the particular building in which the installation is to be made.

The feeding chute 12 and gas discharge flue 11 are contiguous, and have a common vertical wall 31 which effectively separates the two so that air or gas cannot pass from one to the other. The gas discharge flue 11 extends vertically the entire height of the building and communicates with a chimney 32 at the top of the building. The chimney 32 is capped by the usual screen 33.

The feeding chute 12 also extends vertically the entire height of the building and communicates with the chimney 32. The bottom end of the chute 12 communicates directly with the top of the refuse collection chamber 16. Said chute 12 has a number of inlet openings 35 located vertically one above the other, with one such opening 35 being provided at each floor of the building. Each opening 35 is provided with the usual door 36. For convenience, only one opening 35 and door 36 is illustrated in Fig. 1. When the occupant of any floor wishes to dispose of garbage or rubbish, he opens the respective door 36 and drops the refuse down the chute 12 and into the furnace, the refuse landing and accumulating on the grate 18 in the refuse collection chamber 16.

At suitable times as refuse accumulates on the grate 18, the burner is fired and the flame emitted from the nozzle 24 will thoroughly dry said refuse R. After the refuse dries it is subjected to further action of the flame so that it is thoroughly burned.

When the blower 25 is actuated, a steady stream of air at room temperature is directed across the lower end of chute 12. This stream of air forms an effective air shield or screen across the bottom of chute 12 which prevents the hot gases in the furnace 10 from rising directly up the chute 12.

This air shield is made possible by the difference in weight of equal volumes of the hot gases within the furnace 10 and the relatively cold air supplied by the blower 25. It is well-known that if a heavy gas is placed above a light gas, the heavy gas will sink, forcing aside the light gas. It is also common knowledge that to confine a heavy fluid such as water, it is necessary to en-

close the fluid at its bottom and sides, but not necessary to confine the top. Similarly, to confine a light fluid such as a light gas, it is necessary to enclose the fluid at its top and sides, but not necessary to confine the bottom.

Thus, the air emitted by the blower 25, being at room temperature, is denser than the heated gases generated in the furnace 10, so that the air sinks down the chute 12 and into the furnace 10, preventing the heated gases in the furnace from rising up the chute, and forcing aside these gases. The heated gases must then seek another outlet and will be obliged to follow any properly designated channel to a discharge stack.

In the furnace 10, the heated combustion gases in seeking an outlet through the gas discharge chute 11, are made to travel through a devious course through the interior of said furnace, so that the gases may be treated in order to insure complete combustion, and also to remove solid particles carried by said gases.

As the cold air sinks down the chute 12 and enters the refuse collection chamber 16 of furnace 10, it is heated by the flame of the fuel burner and becomes a source of combustion air to assist in the effective combustion of the refuse R. Additional combustion air can, if desired, be introduced through an air inlet opening 37 which is located at the lower end of chamber 16 beneath grate 18.

The hot gasses generated by the burning refuse in collection chamber 16 are effectively confined by the roof and sides of the furnace 10, and by the air seal across the bottom of chute 12. However, as was previously indicated, when the denser atmospheric air introduced through blower nozzle 28 sinks down chute 12, it forces aside the less dense combustion gases, and their only means of escape is through connecting flue 20 to gas discharge flue 11.

The combustion gases within furnace 10 are also subjected to an additional force, the chimney action or drawing action of the gas discharge flue 11. This action is particularly strong in flue 11 but virtually non-existent in chute 12 for several reasons:

In the first place, it is well-known that the natural draft of a chimney is derived from the difference in pressure produced by the difference in weight between the relatively hot gases inside the chimney and an equivalent column of cooler atmospheric air. Since the hot gases in the furnace 10 are directed to the gas discharge flue 11, a draft is created in flue 11, which draft once created, further serves in drawing the hot gases through the furnace 10 to said flue 11.

In addition, it is also common knowledge that a cold stack does not draw except in the presence of a rather strong wind. The air stream introduced by the blower nozzle 28 not only forms an effective seal across the bottom of chute 12, but at the same time keeps the bottom of chute 12 cool. There is therefore little, if any, tendency for the chute 12 to draw, as compared to flue 11.

The hot gases generated by the burning refuse R must, therefore, leave the furnace 10 by the only outlet, the gas discharge flue 11. In flowing to said flue 11, these gases follow the course indicated by the arrows in Fig. 1. The gases enter the combustion chamber 17 where they are subjected further to the flame emitted by the fuel burner nozzle 24, so that they are completely decomposed and rendered odorless. This complete decomposition also eliminates the discharge 75 of smoke from the incinerator. Complete de-

composition is made possible since all of the combustion gases are caused to travel across the length of the furnace 10, instead of being allowed to escape directly up the intake chute 12, as often happens in conventional incinerators.

The combustion gases and heated air leave the interior of the furnace 10 and enter the uptake and connecting flue 20 through the gas passage 21. Any ash, debris, or other solid matter carried by the draft from the burning pile of refuse R across the top of partition wall 15, tends to travel in a straight path, so that its momentum carries it into contact with the baffle wall 19. This solid matter strikes the baffle wall 19 and falls to the bottom of the chamber 17 where it accumulates below the gas passage 21. An access door 38 at the bottom of chamber 17 enables this solid matter to be removed at suitable intervals.

Thus, a portion of the ash and debris carried by the draft is deposited at the bottom of chamber 17. To aid in this removal of solid matter, the gas passage 21 may be made in the form of checkerwork, so that the draft must follow an even more circuitous path. As the air current enters the bottom of uptake flue 20, there are two changes of direction tending to drop the ash and dirt out of suspension in the gas stream and down to the bottom of chamber 17 and uptake flue 20. This debris may be removed, when desired, through an access door 39 at the bottom of flue 20.

The air current then flows through the uptake flue 20, transverse conduit 22, and gas discharge flue 11, to the roof of the building where it is discharged through the chimney 32. Because of the circuitous path which the draft in the furnace 10 is forced to follow, and because of the action of the flame upon the combustion gases in chamber 17, the gas discharged from the chimney 32 is substantially decomposed so that it is odorless, substantially smokeless, and in addition is filtered of substantially all solid matter. Thus, three serious nuisances inherent in the use of conventional incinerators are eliminated.

Since the chute 12 is used for the feeding of garbage and the like to the incinerator, bits of garbage clinging to the side of said chute 12 will tend to decompose, causing disagreeable odors, and also attracting vermin. It is thus desirable, for sanitary reasons, to pass hot gases through chute 12, in order to eliminate these odors and to flush vermin. For this purpose, a damper 40 is located within the transverse conduit 22. This damper may be closed at suitable times, and the furnace fired without operating blower 25, thus causing flame and hot air to travel up chute 12. Damper 40 may also be used to control the draft in furnace 10.

Fig. 2 shows a different type of flue and chute construction which may be used with the furnace just described. The intake chute 12a and the gas discharge flue 11a are again contiguous and are separated by a common wall 31a. The chute 12a, however, does not lead directly to the chimney 32a, but is closed at its top. The upper end of said chute 12a communicates with the flue 11a through an opening 41 in the wall 31a. The opening 41 serves as an outlet through which gases may escape from the chute 12a to the flue 11a and out the chimney 32a, when the damper 40 is closed in order to flush the chute 12a, as previously described.

Fig. 3 shows the air screen or shield of the invention as applied to an incinerator having a top feed chute of any desired length. This type

of incinerator is used mostly in commercial establishments, hospitals, and in the basements of buildings. The incinerator comprises a furnace 50 which is similar to the furnace 10 of Fig. 1. Furnace 50 communicates with an intake chute 51 at one end and with a gas discharge flue 52 at the other end. The intake chute 51 extends vertically to the floor of a building and has a door 53 which is flush with said floor and covers the top of said chute 51. Since it is necessary to open the door 53 and bend over said opened door in order to deposit refuse into the chute 51, it is particularly important to prevent hot air, gases, and flame from escaping up chute 51. This is accomplished by utilizing the same means as previously described, including an identical blower 25 and nozzle 28. Since the furnace is substantially identical with the furnace 10 of Fig. 1, its common parts are identically numbered. It is to be noted, that in this type of incinerator, the chute 51 is completely separated from the flue 52 and is well spaced therefrom. The path of the air current produced by the blower 25 is indicated by the arrows in Fig. 3.

Fig. 4 shows a conventional furnace 60 which does not contain the baffle wall, gas combustion chamber, etc., shown in the furnace 10 of Fig. 1. The intake chute 61 and the gas discharge flue 62 are contiguous and are of the type shown in either Fig. 1 or Fig. 2. The chute 61 and flue 62 both communicate with the top of said furnace 60 at adjacent points. The refuse R which is dropped through chute 61 accumulates on a grate 63 across the entire length of said furnace 60. An externally-located blower 64 forces a stream of air to a plenum chamber 65 and thence through a nozzle 66 which extends through an opening 67 in the outer wall of chute 61. An air shield or screen is thus set up across the lower end of chute 61, preventing hot gases and flame from escaping through said chute 61, in the manner previously described. The path of the air current created by the flue 62 is indicated by the arrows in Fig. 4.

Fig. 5 shows a furnace 70 which is identical in construction to the furnace 10 of Fig. 1, except that it communicates at each end with a feeding chute 71 and gas discharge flue 72, which are completely separated and spaced from each other, similar to the chute and flue arrangement shown in Fig. 3. The blower forces air through the nozzle 28 which extends through an opening 73 in the outer wall of chute 71, to maintain an air shield there-across. The chamber 17 and the bottom of flue 72 may contain respective troughs 74 which are filled with water so that the ash and other debris will collect and be held therein, said troughs 74 being removable for emptying the accumulated ash and debris. A series of water pipes 75 may extend through the interior of the flue 72, so that the hot air and gases escaping through said flue 72 may be utilized to heat the water in said pipes 75. A screen 76 may be diagonally disposed across the bottom of flue 72 in order to insure that any ash or other debris not already collected in the troughs 74 will not rise through the flue 72.

While preferred embodiments of the invention have been shown and described herein, it is obvious that numerous additions, changes and omissions may be made in the invention without departing from the spirit and scope thereof.

We claim:

1. An incinerator comprising a furnace, a gas discharge flue communicating with the interior

of said furnace at one end thereof, a separate upwardly extending feeding chute also communicating with the interior of said furnace at the other end thereof, a nozzle extending transversely the entire width of said chute along one side thereof and having its opening directed transversely toward the other side of said chute, an external blower operatively associated with said nozzle to introduce an unbroken sheet of air into the feeding chute an appreciable distance above the bottom end thereof and to direct said sheet of air downwardly across the lower end of said feeding chute, an upstanding wall within said furnace which divides the lower portion of the furnace interior into a refuse accumulating chamber and a gas combustion chamber, and a fuel burner positioned to eject a flame into said gas combustion chamber and refuse accumulating chamber, said furnace having a baffle wall which separates said gas combustion chamber from said gas discharge flue, said baffle wall having at least one opening therein, said current of air having a lower temperature than the gases generated by the burning refuse within the furnace, said sheet of air covering substantially the entire cross-sectional area of said feeding chute and forming a screen across the bottom of said feeding chute to prevent said gases from rising up said chute and thereby cause said gases to take a devious route through said furnace, over said upstanding wall, through said gas combustion chamber, and through the opening in said baffle wall to said gas discharge flue.

2. An incinerator comprising a furnace, a gas discharge flue an upwardly extending feeding chute and a fuel burner positioned to eject a flame into the interior of said furnace, said gas discharge flue and feeding chute being adjacent and being sealed from each other along substantially their entire height, said feeding chute communicating directly with one end of said furnace, said gas discharge flue having a lower angular extension which extends horizontally along the top of said furnace and vertically along the side of said furnace and communicates with the bottom of said furnace, said furnace having an upright wall which divides the lower portion thereof into a refuse collection chamber and a gas combustion chamber, said fuel burner being located to eject its flame into said refuse collection chamber and gas combustion chamber, said gas combustion chamber having a wall which separates it from said flue extension, said wall having a gas passage at the lower end thereof, said incinerator also having blower means which includes a horizontally-elongated nozzle opening into one side of the lower end of said chute and

extending transversely the entire width of said chute, said nozzle having its opening transversely directed toward the other side of said chute to create an air screen across the width of the lower end of said feeding chute, said air screen preventing the gas generated by the burning refuse in said furnace from rising up said feeding chute, and thereby causing said gas to travel across said furnace, and up said furnace to said gas discharge flue, whereby said gas is subjected to the flame discharged by said fuel burner in said gas combustion chamber, and is caused to follow a generally circuitous route from said gas combustion chamber to said gas discharge flue.

15 3. An incinerator comprising a furnace, a gas discharge flue communicating with the interior of said furnace at one end thereof, a separate upwardly extending feeding chute communicating with the interior of said furnace at one end thereof, a discharge nozzle opening into one side of the lower end of said chute and extending transversely the entire width of the chute, and means operatively associated with the nozzle for introducing a current of air through said nozzle, said nozzle being transversely directed toward the other side of said chute to produce an air stream which flows across the bottom cross-sectional area of said chute and thence into the furnace.

20 4. An incinerator according to claim 3 in which the feeding chute is closed at its top end, said chute communicating adjacent its upper end with said gas discharge flue.

25 5. An incinerator according to claim 3 in which said gas discharge flue and feeding chute are adjacent and sealed from each other along substantially their entire length.
